UNITED STATES PATENT OFFICE.

WILLIAM DIETER, OF NEW YORK, N. Y.

DESIGN FOR A VEHICLE-BODY.

SPECIFICATION forming part of Design No. 36,534, dated September 1, 1903.

Application filed June 20, 1903. Serial No. 162,454. Term of patent 14 years.

To all whom it may concern:

Be it known that I, WILLIAM DIETER, a citizen of the United States, residing in the borough of Brooklyn, city of New York, county of Kings, and State of New York, have invented a certain new, original, and ornamental Design for a Vehicle-Body, of which the following is a specification.

In said drawings, Figure 1 is a view of one side of the vehicle-body, and Fig. 2 is a front view thereof, both views being in elevation.

Having shown my invention, what I claim

as new, and desire to have protected by Letters Patent, is—

The ornamental design for a vehicle-body 15 as shown.

In witness whereof I have hereunto affixed my signature, this 11th day of June, 1903, in the presence of two witnesses.

WILLIAM DIETER.
